MAN'S SUIT OR SIMILAR ARTICLE

Howard S. Foster, 124 Raynham Road,
Merion Station, Pa. 19066

Filed Dec. 28, 1970, Ser. No. 26,648

Term of patent 14 years

Int. Cl. D2—02

U.S. Cl. D2—29

FIG. 1 is a front isometric view of a man's suit showing my new design;

FIG. 2 is a rear isometric view thereof;

FIG. 3 is an enlarged fragmentary view thereof; and

FIG. 4 is a front isometric view of the pants of the suit with the fly in an open position.

I claim:

The ornamental design for a man's suit or similar article, as shown and described.
